(57) **CLAIM**

The ornamental design for a handle for power tool, as shown and described.

DESCRIPTION

FIG. 1 is a perspective view of a handle for power tool according to the invention.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a bottom plan view thereof; and,

FIG. 7 is a top plan view thereof.

In the above drawings, any portions shown in broken lines do not form a part of the invention.
